4 Claims. (Cl. 61—53.6)

Many different types of concrete piles formed in situ are known. There are also many known ways of producing such piles. Some methods include the formation of a foot of special form on the pile. One known method comprises placing concrete in a boring tube or inside a lining inside such a boring tube and then using an inner ram or inner tube with an internal monkey or with an internal ram or valve, the tube is sunk to the required depth for the formation of the foot. A further known method comprises forming the foot or bulb with an internal ram. If a bulb is formed a point is not necessary but an inner tube with a valve is used. The tube is driven by a monkey.

In order to remove some of the difficulties with processes and devices known up to now the inventor already suggested in an earlier invention that the boring tube with the help of gripping jaws or a gripping device could be sealed in relation to the cement or concrete filling at various positions as required. In this manner it is possible first to drive the tube downwards and then to move the tube upwards slightly and to form a bulb-like foot. In an apparatus for carrying out this method the gripping jaws or gripping device in the form of a head are connected with a base plate having a ram and a sealing face movable in such a manner that by moving the face of the suspension device (14 in the accompanying drawings) towards the face of the ram (15) a clamping action is obtained in the tube.

In this older device it was noted that the plug of concrete was detached from the tube owing to its weight and owing to the percussive effect to which the tube was exposed.

One object of the present invention is to ensure that this loosening of the concrete plug occurs in each case and, possibly, obstacles beneath the core of concrete are pressed out of the way.

An illustrative embodiment of the invention is now described with reference to the attached drawings.

FIGURES 1 to 8 are vertical sections illustrating the formation of a pile.

FIGURE 9 is a longitudinal section of the device denoted by general reference 6 in the previous drawings.

FIGURE 10 is a section on the line X—X of FIGURE 9.

In FIGURE 1, 1 denotes the boring tube lying above the ground surface 5. 4 denotes concrete in the tube 1, and 3 denotes a filling funnel for putting in the concrete. The figure is a vertical section.

FIGURE 2 shows the tube in the same position, in section, with the concrete 4 in it. 8 denotes the lower part of a monkey (the rest of the monkey is not shown), while 9 denotes the associated ramming cap. 10 and 11 denote flexible hydraulic leads passing through the cap 9 to the downwardly acting cylindrical jack or pressure device 2 which contains within it a piston 14 (shown in FIG. 9). The jack 2 is placed below a locking or grip-

2

ping device 6 suspended by a rope 7. This gripping device is described in more detail below with reference to FIGURES 9 and 10.

FIGURE 3 shows the jack 2. It also shows in section the tube 1 which has already been rammed into the ground with the concrete filling 4 in it. The tube 1 is sunk to the necessary depth by means of the monkey 8.

FIGURE 4 is a section of the device shown in FIGURE 3 with the cap 9 and the monkey 8 removed. The ram 13 has been hydraulically driven and owing to the actuation of the gripping device 6 the tube has been raised somewhat. Consequently the concrete below the tube 1 has spread out.

FIGURE 5 is a section and elevation of the same parts as shown in FIGURE 4 together with the parts 8 and 9. It is to be seen that the tube 1 with the gripping device 6 in the active position has been driven further into the ground after which the gripping device 6 is released and the piston 14 (FIG. 9) is driven back in the jack 2 hydraulically.

As shown in FIGURE 5, the whole tube 1 with the stationary device consisting of the elements 2, 6, and 13 is driven down in the direction of the arrow with the help of the monkey 8 so that the tube is driven further into the earth. The foot 12 is then expanded as shown and the structure takes on the form as shown in FIGURE 6. As shown in this figure the reinforcement 24 is in place while the funnel 3 is in position for charging in concrete. Before the reinforcement 24 is put in place it is, of course, necessary to remove the cap 9, to release the elements 2, 6, and 13 hydraulically and remove it by means of the rope 7.

FIGURE 7 shows the structure as shown in FIGURE 6 after removal of the funnel 3. The hydraulic device consisting of 2, 6, and 13 has been placed in position for consolidating the concrete and for moving the tube 1 in steps upwards with the gripping device 6 in the active position. The final result is shown in FIGURE 8.

By additional blows on the concrete column or pile above the foot 12 it is possible to use the foot 13 to form further bulges in the concrete column of any desired vertical dimension at any required height.

FIGURE 9 shows a section of part of the device denoted by the general reference 6 in the previous figures. Reference numeral 2 again denotes the downwardly acting jack and 13 denotes the ram of the piston 14 in this jack. 15 denotes an oil supply pipe and 16 an oil return pipe. The direction of flow in these pipes can be reversed to allow the jack to act in both directions. The pipe 15 is connected with the oil pipe 10 and the pipe 16 with the oil pipe 11. The pipes 11 and 10 open into the jack at the positions 26 and 25 respectively. The suspension cable or rope 7 is secured to an eye 27 in the part 21.

FIGURE 10 is a section on the line X—X of FIGURE 9 and shows that the part 17 is tapered (see FIGURE 9) so that during lowering of the cylinder 21 and simultaneous raising of the piston 20 by passing pressure oil through pipe 16 into cylinder 21, the wedge 17 connected at its upper end to the piston 2 will be raised while the parts 18 connected by the links 22 at 23 to the cylinder 21 will be simultaneously lowered to press outwards the parts 18 so that the whole device is held fast in the tube 1.

This effect is heightened since simultaneously the piston 14 presses the ram 13 against the part 2 and

against the wedge 17, pressing the latter upwards so that the parts 18 and the rubber parts 19 are pressed against the wall of the tube. The rubber parts 19 attached in any well known manner to parts 18 serve to prevent the entry of dirt particles to the gap and also during release of the gripping device to press the parts 18 away from the tube 1.

The pressing away effect with the help of the part 13 is accomplished in such a manner, as shown in FIGURE 9 that the part 13 is supported in relation to the concrete layer 4.

What I claim is:

1. A method for the production of concrete piles in situ comprising the steps of filling at least the lower end of an upright tube open at both ends with concrete while the lower end of the tube engages the ground for forming a concrete plug in said lower end; anchoring a pressure device in the interior of the tube in engagement with the upper end of the concrete therein; imparting impacts onto the upper end of the tube for driving the lower end of the tube with the concrete plug therein into the ground while preventing with said anchored pressure device the plug from moving upwardly in the tube; exerting by means of said anchored pressure device a downwardly directed pressure onto the concrete plug to move the latter downwardly with respect to the tube while simultaneously transmitting through said anchored pressure device the counterpressure created by said pressure to the tube to raise the latter so that part of said plug will be located in the ground below the lower open end of the tube; and driving the tube further into the ground by imparting impacts onto the upper end thereof while preventing with said anchored pressure device the remaining part of the plug in the tube to move upwardly with respect thereto to compress the part of the plug located below the lower end of the tube in axial direction and to cause it to expand laterally beyond the tube.

2. A method for the production of concrete piles in situ comprising the steps of filling the lower end of an upright tube open at both ends with concrete while the lower end of the tube engages the ground for forming a concrete plug in said lower end; anchoring a pressure device in the interior of the tube in engagement with the upper end of the concrete therein; imparting impacts onto the upper end of the tube for driving the lower end of the tube with the concrete plug therein into the ground while preventing with said anchored pressure device the plug from moving upwardly in the tube; exerting by means of said anchored pressure device a downwardly directed pressure onto the concrete plug to move the latter downwardly with respect to the tube while simultaneously transmitting through said anchored pressure device the counterpressure created by said pressure to the tube to raise the latter so that part of said plug will be located in the ground below the lower open end of the tube; driving the tube further into the ground by imparting impacts onto the upper end thereof while preventing with said anchored pressure device the remaining part of the plug in the tube to move upwardly with respect thereto to compress the part of the plug located below the lower end of the tube in axial direction and to cause it to expand laterally beyond the tube; removing said pressure device from the tube; filling the remainder of the tube nearly up to but short of the upper open end thereof with concrete; anchoring said pressure device in the region of the upper end of the tube; exerting by means of said anchored pressure device a downwardly directed pressure onto the upper surface of the concrete in the tube while simultaneously transmitting through said anchored pressure device the counter pressure created by said pressure to the tube to raise the latter through a given distance; lowering said pressure device in the tube and reanchoring the same at a lower portion of the tube; exerting by means of said anchored pressure device a downwardly directed pressure onto the upper surface of the concrete in the tube while simultaneously transmitting through said anchored pressure device the counter pressure created by said pressure to the tube to raise the latter through a given distance; and repeating the last two steps until the tube is completely raised out of the ground while a concrete pile with a bulbous end is formed in the ground.

3. A method for the production of concrete piles in situ comprising the steps of filling the lower end of an upright tube open at both ends with concrete while the lower end of the tube engages the ground for forming a concrete plug in said lower end; anchoring a pressure device in the interior of the tube in engagement with the upper end of the concrete therein; imparting impacts onto the upper end of the tube for driving the lower end of the tube with the concrete plug therein into the ground while preventing with said anchored pressure device the plug from moving upwardly in the tube; exerting by means of said anchored pressure device a downwardly directed pressure onto the concrete plug to move the latter downwardly with respect to the tube while simultaneously transmitting through said anchored pressure device the counterpressure created by said pressure to the tube to raise the latter so that part of said plug will be located in the ground below the lower open end of the tube; driving the tube further into the ground by imparting impacts onto the upper end thereof while preventing with said anchored pressure device the remaining part of the plug in the tube to move upwardly with respect thereto to compress the part of the plug located below the lower end of the tube in axial direction and to cause it to expand laterally beyond the tube; removing said pressure device from the tube; placing a reinforcement into the interior of the tube extending in longitudinal direction therethrough; filling the remainder of the tube nearly up to but short of the upper open end thereof and around said reinforcement with concrete; anchoring said pressure device in the region of the upper end of the tube; exerting by means of said anchored pressure device a downwardly directed pressure onto the upper surface of the concrete in the tube while simultaneously transmitting through said anchored pressure device the counter pressure created by said pressure to the tube to raise the latter through a given distance; lowering said pressure device in the tube and reanchoring the same at a lower portion of the tube; exerting by means of said anchored pressure device a downwardly directed pressure onto the upper surface of the concrete while simultaneously transmitting through said anchored pressure device the counter pressure created by said pressure to the tube to raise the latter through a given distance; and repeating the last two steps until the tube is completely raised out of the ground while a concrete pile with a bulbous end is formed in the ground.

4. A method for the production of concrete piles in situ comprising the steps of filling at least the lower end of a tube open at both ends with concrete for forming a concrete plug in said lower end; imparting impacts onto the upper end of the tube for driving the lower end of the tube with the concrete plug therein into the ground while preventing the concrete plug from moving relative to the tube; exerting downwardly directed pressure onto the concrete plug to move the latter downwardly with respect to the tube while transmitting the counter pressure created by said pressure to the tube so as to raise the latter so that part of the plug will be located in the ground below the lower open end of the tube; driving the tube further into the ground by imparting impacts onto the upper end thereof while preventing the part of the plug remaining in the tube to move upwardly with respect thereto to compress the part of the plug located below the lower end of the tube in axial direction and to cause it to expand in radial direction; filling the tube close to the upper end thereof with concrete; and exerting onto the upper end of the concrete in the tube a downwardly directed pressure while simultaneously transmitting

5
ting the counter pressure created by said pressure onto
the tube to gradually raise the latter.
